WARP CORD TENSING MEANS FOR LOOMS

Frederick H. Blake, 1045 91st NE., Bellevue, Wash.

Filed Apr. 21, 1959, Ser. No. 807,849

7 Claims. (Cl. 139—104)

This application relates to stick weaving looms and more particularly to tensioning means for warp cords used on stick weaving looms. This present application is a continuation-in-part of a U.S. patent application filed by me under Serial No. 549,361 on November 28, 1955, and entitled "Stick Weaving Loom."

The weaving of slat-like materials of small dimensions into materials of sufficient width so that it can be hung with the slats vertical or horizontal and serve as curtain material, room dividing material, and also as closures for door openings, has developed special problems, outstanding is the fact that it is found necessary to use a greater beating force than in other looms, in order that the successive slats will be driven home uniformly, close together, and in a parallel relationship at right angles to the longitudinal axis of the woven material. In such weaving the warp cords are normally much stronger than in the weaving of cloth and similar materials and in order to function properly with the heavier beating strains imposed upon the cords a much greater tension is of necessity imposed upon them. In such weaving it is sufficient to have warp cords pass through spring compressed tensioning devices. Such devices normally can safely and with uniformity impose tensions of from 0 to approximately $\frac{3}{4}$ of one pound. However in this form of weaving, wherein sticks are employed, it has been found most desirable to employ greater tensions of the order of approximately three pounds on each of the warp cords. This is far beyond the capacity of the type of tensioning devices which rely upon friction caused by two parallel surfaces tending to grip the cords. In this present invention, roller tensioning means are provided to the end that very substantial tensioning can be provided, and it has been found most desirable to use the compression of friction type tensioners in association with the roller means, wherein the older form of tensioners may be considered back tensioners to maintain snubbing strain on the roll tensioners 17 and 18 and as adjusting or vernier means to achieve the exact tension required on certain of the cords, or to provide uniform tension throughout.

A principal object of this invention therefore is to provide means which are capable of successfully and uniformly applying the increased tension required on the warp threads when the same are used in the weaving of slat or stick materials, and to maintain constant and even tension on the longitudinal threads while periodically inserting thin slats or strips of stiff material at right angles to these threads.

A further object of this present invention is to provide shaft means around which the warp cords are wrapped and which cords provide the rotative force for the shafts which are otherwise not provided with turning means.

A further object of this invention is to provide roller tensioning means wherein the roller may be provided with friction drag means so that the tensioning of the cords by the roller can be varied within operational limits, and under extreme cases of tensile requirements to

2

provide a roughening of the cord engaging surfaces to increase the friction available.

A further object of this invention is to provide a plurality of rollers turning at the same angular speed but with in the rollers, themselves, are of different diameters.

A further object is to provide intermittent braking means for stopping the rotation of the tensioning roller or rollers during the beating period and having this same interconnected with the rollup roll of the loom so as to 10 synchronize the dead periods of the two rolls, and thus prevent the slackening of the warp cords or placing unusual strains on them.

Further objects, advantages and capabilities will be apparent from the description and disclosure in the drawings, or may be comprehended or are inherent in the device.

In the drawings:

Figure 1 is a plan view of one type of loom to which this present invention may be successfully applied;

Figure 2 is a side elevation of a portion of the loom of Figure 1;

Figure 3 illustrates in a fragmentary side elevational view the braking means for a tension producing roller and switching means therefor;

Figure 4 is a perspective view in fragmentary form showing two parallel tensioning shafts and the manner in which the warp cords are wound around the same;

Figure 5 illustrates a common form of back tensioning means which has been found very satisfactory for use 30 with this present tensioning means provided by one or more of the shafts of Figure 4 and to act as a vernier or adjusting means therefor;

Figure 6 is a fragmentary elevation partly in section 35 illustrating one of the switches actuating the electrical system;

Figure 7 is a schematic electrical diagram illustrating the electrical connections between the brake of the tension roller and the motive power for the windup roll to insure synchronous action of these two means;

Figure 8 is a top plan view showing the motor which drives the windup roll and showing the use of a magnetic clutch as a means for stopping and starting the windup roll;

Figure 9 is a fragmentary vertical sectional view of the 45 adjustable friction means, taken along line 9—9 of Figure 2;

Figure 10 is a diagrammatic view showing the proportion of a single stick weaving cycle employed to place the stick, to complete the beating, and illustrating the 50 proportional time to complete the shaft braking cycle.

Figures 1 and 2 show, in addition to the subject matter of this present invention, sufficient of a typical stick weaving loom so that the association of the tensioning means with a loom of this type can be more thoroughly discussed.

Referring more particularly to the disclosure in the drawings, throughout which like reference characters indicate like parts, the numeral 10 designates the frame of a stick weaving loom of the type suitable for the employment of my present tensioning means.

Fixedly secured to frame 10 is a vertically disposed frame member adapted to support a plurality of shafts 11, upon which are revolvably positioned a large number of spools of cord 12 forming the warp. After leaving spools 12, cords C are lead to convenient guiding means so as to bring the cords substantially in alignment with their final portion on the loom. The cords are then passed through grommeted openings in the flange of the tensioner supporter 13 and divided by collared bolts 14, as will probably be best understood from a study of Figure 5 of the drawings. The cords are next crossed over to

the opposite hand and placed between the spring loaded flanges of the tensioners 15. The threads are then re-crossed and lead around the collared bolts 16 through grommeted holes in the second flange of the tensioner support. Tensioners 15 are well known in this field and are used to provide that the spring urged plates may be adjusted to provide the desired frictional engagement with the cords within their capacity.

The dependable working range of tensioners of the type illustrated is from 0 to $\frac{3}{4}$ of one pound. As approximately three pounds of tension is required in this loom the bulk of the tension load is achieved by a plurality of rolls, to be described. The tensioners 15 may therefore be considered back tensioners for the roll tensioners and as an adjusting or vernier means to achieve the tension required on certain of the cords, or to provide uniform tension throughout.

The threads or cords C are then passed over and once around shafts 17 and 18, which shafts are mounted transversely of the frame 10 and are at right angles to the direction of movement of the threads. The threads first are passed over shaft 17, under said shaft and brought through to the right of the respective sides. They are then passed over shaft 18, under said shaft and brought through to the left of their respective sides. This shifting from right to left compensates for the lay or twist of the threads which are cord-like and consist of the plurality of yarns which are twisted into a thread or cord. It has been found that unless this arrangement is provided, the threads will travel to the right at all times due to the lay of the threads and tension will be increased by irregular amounts and, in some cases, may bind and break the threads. Shaft 18 is of slightly larger diameter than shaft 17, this difference being in the order of three thousandths of an inch (.003") on an overall shaft diameter of one and three eighths inches (1 $\frac{3}{8}$ "). Means are provided to insure that shafts 17 and 18, however, travel at the same rotary or angular speed. One means for providing this relationship is illustrated in Figure 2, in which it will be noted that a sprocket is secured to each of shafts 17 and 18 and they in turn are connected by a chain 29. A preferred arrangement employs an idler, as illustrated at 19, so that adjustment can be made on the connecting chain.

Within the idler sprocket a torque adjustment device of conventional design may be advantageously employed. A simplified form of torque device is illustrated in Figure 9 in which bearing bolt 21 is keyed to and supported by frame 10. A pair of coating thrust washers 22 and 26 are employed, the same being keyed, 22 to bolt 21 and 26 to sprocket 19. Frictional adjustment, which controls the torque available through chain 29 to shafts 17 and 18, is made by lock nuts 27 and washer 30. Shafts 17 and 18 are operated solely by the friction created by the wrap-around cords C, which are under tension supplied by the main woven material take-up roll 58. Shaft 18 having a larger diameter than shaft 17, but operating at the same r.p.m., puts a tension of a few pounds on the threads. This provides a differential between the two rolls 17 and 18. The friction clutch or torque device incorporated in the idler may be employed to slow down the speed of both rolls slightly and thus put an overriding tension on the cords. This same means may be used if only one of the shafts is employed, as may be desirable where maximum tension is not required. In such cases it is usually desirable to increase the diameter of the shaft.

The threads or cords are passed to a suitable shedding arrangement where the strips are introduced between the cords as weaving requires. With the placement of each strip the beater, as 28, must be moved forward to properly seat the successively positioned strips. The shedding and beating arrangements form no direct part of this application but one example is given in my co-pending application, Serial No. 549,361. However, during

the beating action the power application to the woven material windup roll 58 needs to be interrupted and during the period the roll 58 is stationary shafts 17 and 18 must be stopped and held in order to hold the warp threads or cords under tension. The necessity of precise sequential timing indicates the need of joining the actuating means for the beater operation, the windup roll and the brake for rolls 17 and 18 in a single electrical unit. Reference is now made to Figure 7 in which the essential electrical elements are shown schematically.

In the operation of this equipment, starting with introduction of a new strip S, the desirable sequence is substantially: as strip S completes its movement through the space provided between cords C it trips the electric switch 46 which actuates a suitable beater bar 28 and its supporting framework which drives strip S into its final position in the woven material and then returns the beater bar to its rest position. The final return movement of the beater bar assembly partially rotates shaft 54 and actuates switch 44, which switch has a two-fold purpose. Referring back to the period when the beater bar strikes the strip of wood home to its final position, the bar engages bayonet member 55 attached to switch 56 and this switch energizes the magnetic clutch 70 controlling windup motor 57. Bayonet member 55 is urged upwardly by spring means to de-energize switch 56. When sticks S overlay cam portion 73 the bayonet member is depressed and switch 56 energized and the windup roll is operated once for each stick until the sticks are all in place. It is to be noted that switch 56 merely energizes the magnetic clutch switch, but does not complete the circuit. The circuit is actually completed when countershaft 54 by its rotation, caused by the return of the beater bar, actually trips switch 44.

When the windup motor 57, which serves to wind up the entire bolt of material that has been woven, is in operation the windup roll 58 is moved by a chain reduction drive 159 connected to the magnetic clutch 70 by the right angle gear box 154. When the windup roll has moved to a point allowing bayonet member 55 to return to its normal position the circuit is broken. The magnetic clutch is instantaneously engaged and solenoid 45, through a suitable linkage, actuates brake 59 on shaft 18. It is to be noted that throughout this mechanism accurate timing is very essential and in order to actuate the parts, some of which are relatively large, it has been found desirable that the main energizing be accomplished by electric motors or air cylinders, neither one of which function instantaneously; and it is for this reason that a preferred form of construction employs solenoid releasing means having actuating members of small mass to the end that accurate and exact timing can be achieved.

Fig. 10 illustrates by diagram the proportion of a complete cycle required to feed and weave one stick in place. In this illustration the complete cycle is assumed to be one second. It is to be noted that the time to load one stick into the shed is 0.4 second, and that loading starts at 0.0 second. The time to shift the shed is 0.1 second starting at 0.4 and ending 0.5. The beater, being an element of appreciable mass, requires .25 second starting at 0.4 to move into contact with the new stick S. The beater "dwell time" 0.1 second starting at 0.65 is consumed in driving the stick home and holding it in position until the "beater back" portion of the cycle starts at 0.75 second. The brake on shaft 18 must be locked on, during the period, 0.5 to 0.9 but the brake requires .05 second to set and the same period to release. Power must also be disconnected from the windup roll 58 during the beating period, when the brake is locked. The windup roll has the tension of all the cords on it and stops as soon as power is interrupted.

It is believed that it will be clearly apparent from the above description and the disclosure in the drawings that the invention comprehends a novel construction of a warp cord tensing means for looms.

Having thus disclosed the invention, I claim:

1. A cord tightener for a loom, comprising: a pair of tension shafts extending transversely of a loom frame in closely spaced apart relationship and said shafts rotating at different peripheral speeds, and the warp cords in said loom having turns about said tension shafts; means are provided for insuring that said pair of tension shafts will rotate at the same angular speed and adjustable friction means adapted to vary the force required to revolve said shafts and thus provide an additional means for varying the tension imposed on said warp cords.

2. A cord tightener for a loom, comprising: a pair of tension shafts extending transversely of a loom frame in closely spaced apart relationship and said shafts rotating at different peripheral speeds, and the warp cords in said loom having turns about said tension shafts; said pair of tension shafts are provided with roughened warp cord engaging surfaces, each being uniformly configured throughout their respective portions which are engaged by said warp cords.

3. A cord tightener for a loom, comprising: a loom frame supporting cord feeder means at one end and a driven woven material roller at the other; a spring loaded tensioner next to said feeder means which has opposed adjustable spring-loaded surfaces between which cords pass and which restrain said cords and a tension shaft between said tensioner and said roller, said tension shaft having electrically operated brake means adapted to stop the rotation of said tension shaft when it is fully applied; said tension shaft extending transversely of the path of travel of cords and the cords passing around said tension shaft and said tension shaft having speed control means whereby it may be caused to rotate at peripheral speeds of less than the lineal speed of the cords after said cords leave said spring-loaded tensioners.

4. The subject matter of claim 3 in which said tension shaft has its cord engaging surface uniformly roughened throughout its length to increase the friction of the cord as it passes around said tension shaft.

5. The subject matter of claim 3 in which said driven

10 5 woven material roll and said tension shaft are provided with means synchronizing the interruption of the motive power of said roll and the operation of actuating means for said electrically operated brake to insure the stopping of said roll and said shaft during the beating cycle of a loom to which said cord tightener is operatively secured.

15 10 A cord tightener for a loom, comprising: a loom frame supporting cord feeder means at one end and a power driven woven material roller at the other, a spring loaded tensioner next to said feeder means which has opposed adjustable spring-loaded surfaces between which cords pass and which restrain said cords and a pair of tension shafts between said tensioner and said roller extending transversely of the path of travel of cords and the cords passing around each tension shaft and said tension shafts having means whereby they rotate at different peripheral speeds with the lesser peripheral speed occurring on the shaft which the cords pass around first after leaving said tensioners and brake means for stopping 20 15 the rotation of said tension shafts.

25 20 The subject matter of claim 6 in which said driven woven material roller and said pair of tension shafts are provided with electrically operated means synchronizing the interruption of motive power of said roll and the actuating means for said power operated brake to insure the stopping of said roll and said shaft during the beating cycle of a loom to which said cord tightener is operatively secured.
